VENTILATED LAMPHOLDER

Donald G. Kimball, Stratford, Conn., assignor to
General Electric Company, a corporation of
New York

Application September 18, 1947, Serial No. 774,719

1 Claim. (Cl. 240—81)

1

The present invention relates to lampholders, particularly lampholders for incandescent lamps. Still more particularly, the present invention relates to lampholders for so-called portable lamps.

It is an object of my invention to provide an improved lampholder, particularly for portable lamps, in which provision is made for definitely locating the lamp with respect to a diffuser, shade, or reflector in order to obtain a desired light distribution from the lamp. A further object is to provide a lampholder with improved ventilation for the lamp base. A still further object is to provide a lampholder combined with a switch in which an element of the switch assists in positioning the lamp socket. A still further object is to provide a lampholder and switch combination adapted for mounting in a husk having improved ventilation for the purpose of maintaining the switch at a low operating temperature. A still further object is to provide a lampholder and switch combination for husk mounting arranged to facilitate assembly and wiring of the unit.

The above and other objects of my invention will best be understood from the following description taken in connection with the accompanying drawing in which Fig. 1 is an elevation of a table lamp embodying my invention, parts of the lamp being shown in section; Fig. 2 is a vertical section through my lampholder; Fig. 3 is a vertical section taken at right angles to that of Fig. 2 namely along the line 3—3; and Fig. 4 is a plan view of my lampholder.

As previously indicated, my lampholder is especially adapted for use with portable lamps commonly known as table or floor lamps, although my invention is not so limited. In order to facilitate the description of my invention, I have, however, shown it as applied to a table or floor lamp.

Referring now to the drawing, my lampholder is shown mounted in a husk 1 which may generally be of conventional shape and size. It may be fabricated in any desired manner, but is preferably provided with a shoulder 2 on which my lampholder is supported. The shoulder 2 may conveniently be formed in the spinning or pressing of the husk, when this is made of sheet metal, but it will be understood that with respect to some features of my invention the shoulder 2 or an equivalent thereof may be formed in any other desired manner so long as adequate support is provided to support the lampholder within the husk in an axial direction and to center the lampholder, as will presently appear. I prefer, how-

ever, to use a husk with a shoulder substantially as shown in the drawing.

The bottom of the husk has a central hole 3 above which a threaded nut 4 is secured, preferably by brazing or welding. Reinforcing washer 5 may be interposed between the nut and the bottom of the husk shell. By means of the threaded nut 4, the husk may be mounted on the end of any pipe or rod such as is customarily used for the assembly of portable lamps. In Fig. 1 the lamp is illustrated by way of example as consisting of a base 6 and a decorative tube 7 through which extends a pipe 8 carrying power supply wires 46. As shown in Fig. 1, the husk 1 may be directly mounted on the pipe 8. Any other suitable mounting of the husk may, of course, be used if desired. In bridge lamps the husk may, for example, be mounted from the side instead of from the bottom.

20 The husk 1 is open at the top and my lampholder and switch combination are inserted into the husk through this opening. My lampholder includes a cup or receptacle 9 within which the lamp socket is mounted. The cup 9 is preferably molded from heat resisting, electrical insulating material. The outside of the cup 9 is provided with a peripheral flange 10 which may be made integral with the body of the cup 9. In the preferred construction, however, the flange 10 is formed by sheet metal ring whose internal diameter is such as to fit snugly over the bottom of the cup 9 so as to abut a narrow shoulder 11 formed in the outer periphery of the cup. In order to fasten the ring 10 to the cup 9, the ring may have a plurality of inwardly projecting tangs 35 12 which are just long enough to press against the cup 9 and bite into the cup wall to prevent the ring from dropping off the bottom of the cup. The outside diameter of the ring 10 fits into the upper part of the husk 1 so as to rest on the shoulder 2 which thus forms a seat to support the lampholder within the husk. Thus the ring 10 simultaneously centers the cup 9 within the husk.

45 The lamp socket which is mounted within the cup 9 comprises a conventional screw shell 13, of conducting material such as brass, having legs 14 and 15 bent inward at the bottom to provide supporting feet 16 and 17. The shell 13 is supported and centered within the insulating cup by means of screws 18 which pass through holes in the feet 16 and 17 and in the bottom of the cup 9. It will be understood that the shell 13 serves as one electrode for the conventional screw base incandescent lamp. Since the embodiment of my invention herein described is intended for use

with two filament lamps, two additional electrodes are provided to complete the lamp socket. A ring electrode 19 having a supporting foot 20 is fastened to the bottom of the cup by means of the screw 21 and a central electrode 22 is secured to the bottom of the cup by screw 23. The central electrode 22 may be of spring material, but in order to insure adequate central contact with the lamp at all times I prefer to use a coil spring 24 beneath the central portion of electrode 22, the spring 24 being located in a central cup-shaped depression 25 at the bottom on the insulating cup 9. The ring electrode 19 is preferably supported by ribs 26 extending upwardly from the bottom of the cup 9. Parallel ribs 27, likewise extending upwardly from the bottom of the cup, provide positive lateral positioning of the electrodes and isolate the securing screws 21 and 23.

Inasmuch as considerable leverage exists when grasping the bulb 29 of an incandescent lamp which is being screwed into the socket 13, considerable force may be exerted on the shell 13 tending to displace it from the central axis of the lamp. In order to prevent such displacement and to limit lateral motion of any part of the screw shell 13, inwardly projecting vertical ribs 28 are formed on the interior surface of the cup 9. It will be observed that the described construction insures the centering of the lamp bulb 29 on the axis of the lamp since the socket shell 13 is prevented from becoming displaced in the cup 9, and the cup 9 is centered in the husk 1 by means of the flange 2. It follows that since the lamp bulb 29 is always centered with respect to the husk 1 it will also be centered with respect to a diffuser 30 and shade 31 when these are suitably mounted on the husk, as illustrated, for example, in Fig. 1.

The lampholder so far described may be anchored against rotation in the husk and against vertical movement in any desired manner. I prefer, however, to use for this purpose an element of a switch 32 which, according to my improved construction, is directly mounted on the under side of the insulating cup 9 with the aid of the electrode securing screws 21 and 23. The latter are preferably arranged to serve at the same time as conducting members for supplying current from the switch to the lampholder electrodes. The switch 32 is preferably a snap switch having a plurality of positions to provide varying degrees of illumination intensity by energizing the filaments of a multifilament lamp singly or in combination as is well known in the art. The switch may be operated by turning a laterally extending knob or button, although I prefer to use and have illustrated a lever operated switch which may be actuated by switch handle 33. Moreover, I prefer to arrange the fastening of the switch handle 33 to the switch body in such a way that it can readily be removed while the lampholder and switch unit is being mounted in the husk. In my preferred construction where a lever operated switch is used, the handle 33 is threaded into the switch operating lever. I also prefer to have the switch handle so connected to the switch mechanism and so mounted in the husk that when the handle is horizontal, the switch is in "off" position, when inclined downwardly, a low level illumination is produced by the lamp and when inclined upwardly a high level of illumination is produced by the lamp. Switches suitable for this purpose are known in the art, but automatic indication of the intensity

of the selected illumination level is only secured by properly mounting the switch in a husk as herein disclosed.

The switch 32 is rigidly fastened to the bottom of the receptacle cup 9 by means of screws, which at the same time also serve as conducting elements to carry current from the switch to the socket electrodes and to secure the socket switch and receptacle together into a single unit. As shown in Figs. 2 and 3, the switch is secured to the receptacle by three such screws which are threaded into switch terminal extensions or fixed contact extensions having feet which abut the bottom of the receptacle 9. Thus one terminal extension 41 receives the screw 18 which simultaneously serves as one fastening for the screw shell 13 and as an electrical connection thereto. Fixed contact 42 has an extension with a receptacle abutting foot 43 into which the screw 23 is threaded and which simultaneously serves to conduct current to the center electrode 22. A third mechanical fastening and electrical connection is made from fixed contact 45 which has an extension 44 into which screw 21, securing ring electrode 19, is threaded.

In order to carry out my preferred manner of securing the lampholder against rotation and axial movement in the husk, the switch 32, in addition to being firmly mounted beneath the insulating cup 9, is provided with a nozzle 34 through which the operating handle 33 extends. A suitably located perforation 37 is made in the wall of the husk 1 to receive the nozzle 34. The latter is externally threaded and is secured in the hole 37 in the wall of the husk by means of a nut 35 on the inside of the husk and a threaded knurled ring nut 36 on the outside.

If the diameter of the hole 37 be made only just large enough to receive the nozzle 34 and if the center of the hole be located the proper distance from the shoulder 2 of the husk, it is evident that the switch nozzle will then secure the lampholder from rotation within the husk and will simultaneously prevent axial motion of the lampholder in the husk. My removable switch handle and nozzle mounting also avoids an unsightly slot in the husk wall since the round nozzle mounting hole 37 is completely covered by the knurled ring 36. Furthermore, my arrangement for mounting a lampholder in a husk greatly simplifies the assembly operation since the lampholder and switch unit need only be dropped into the husk until the ring 10 seats on the shoulder 2 and the unit rotated until the nozzle 34 is opposite the hole 37 after which the nozzle is readily positioned through the hole. Threading the knurled ring 36 onto the nozzle and securing the handle 33 to the switch completes the assembly operation. My mounting arrangement is completely independent of the supporting standard 7 or pipe 8. This is an additional advantage because no hickey is required and the connecting wires are not likely to become twisted during assembly.

It has heretofore been proposed to mount a control switch for a portable incandescent lamp within the husk which carries the lamp holder. In the large sizes of lamps, particularly mogul base multi-filament lamps, difficulty has been experienced in obtaining a suitably long life for the switch. One reason for the short life of switches as heretofore used has been the high temperature to which the switches were subjected. The construction of my lampholder provides improved ventilation, whereby the temperature of the

switch may be held down to a reasonable value. Since both the lamp base and screw shell 13 are of metal, they are excellent conductors of heat and tend to conduct heat from the lamp into the lampholder and thence to the switch 32. I, therefore, have arranged my lampholder and its mounting within the husk in such a manner that a strong draft of air is made to flow through the husk first around the switch and then directly around the lamp shell 13 and the lamp bulb as indicated by the arrows in Fig. 3. This flow of air I secure by making effective use of convection caused by the heat of the lamp 29, and by arranging the lampholder parts so that substantially all of the convection air current flows out of the husk through perforations in the bottom of receptacle 9 and between its walls and the shell 13.

Flow of air into the husk is obtained through a plurality of holes 38 at the base of the husk. The internal diameter of the cup 9 is made appreciably larger than the diameter of the shell 13 providing a considerable, although limited, space 39 between the shell and cup. Perforations 40 are made in the bottom of the cup in line with the annular space 39 surrounding the shell 13. These perforations 40 permit air to flow from the interior of the husk body into the cup 9 through the space 39, thereby cooling the shell 13 and the base of the lamp. Thence the air flows upward along the neck of the lamp bulb. In order to create a strong draft through the openings 40, the ring 10, which also supports the lampholder in the husk, is designed substantially to close the space between the outer wall of the cup 9 and the wall of the husk. Therefore, substantially all of the air which enters the husk through the holes 38 must flow through the openings 40 in the bottom of the cup 9 and directly in contact with the shell 13 and the lower part of the lamp. It will also be noted that the direction of air flow is such that the air, while still cool, first passes around the switch 32 before reaching the much hotter lamp shell 13. With the arrangement described, I have found that the temperature to which the switch 32 is subjected can, in the case of 100-300 watt, two-filament lamps, be reduced as much as 40° F., thereby greatly prolonging the life of the switch and lampholder.

While I have shown and described a particular embodiment of my invention, it will be obvious to those skilled in the art that various changes and modifications may be made without departing from my invention in its broader aspects and I, therefore, aim in the appended claim to cover all such changes and modifications as fall within the true spirit and scope of my invention.

What I claim as new and desire to secure by Letters Patent of the United States is:

A combination husk and lampholder unit for portable lamps in which the lampholder is adapted to support and energize an incandescent filament lamp in a base-down position, said unit comprising a lampholder including a cup-shaped receptacle of insulating material having bottom and side walls, a lamp socket having a metallic shell mounted in fixed position in said receptacle and adapted to receive and support the metallic base of a lamp in intimate thermal contact with the shell, said socket shell being spaced from the side wall of said receptacle to form an air flow space between said shell and wall, said receptacle having air passage openings at the bottom thereof communicating between the exterior of said receptacle and the bottom of said air flow space, a husk open at its upper end and having air inlet openings at its lower end, and means unobstructive of said air passage openings in said receptacle for mounting said receptacle within said husk near the open end thereof, said mounting means including an outwardly extending ring secured to and encircling the outer side wall of said receptacle and an inwardly extending shoulder in said husk adapted to form a seat for said ring, and said ring substantially closing the space between the husk wall and the exterior wall of the receptacle, whereby a convection path for cooling air is provided from the exterior of the husk through said air inlet openings in the husk, thence through said air passage openings in the receptacle and into and through said air flow space for cooling the socket shell and interior wall surfaces of the receptacle.
